UNITED STATES PATENT OFFICE

FRANK DITCHFIELD, OF CLEVELAND, OHIO, ASSIGNOR TO THE YOUNGSTOWN STEEL
DECOR COMPANY, OF CLEVELAND, OHIO, A CORPORATION OF OHIO

DOOR

Application filed April 15, 1929. Serial No. 355,057.

This invention relates to improvements in doors.

In the manufacture and operation of railway car doors of the sheet metal type one of the greatest difficulties is to obtain sufficient rigidity, consistent with reasonable weight, in the edges and more particularly the vertical edges. Many factors, such as weaving of the car bodies, lodging of the load against the doors, rough methods of forcing the doors opened and closed and striking against the doors while trucking loads in and out, all tend to induce bending, distortion and twisting of the edge portions of the door.

One object of my invention is to provide an arrangement which will have greater strength along the door edges than heretofore without increase of weight or material.

Another object of my invention is to provide a door of the sheet metal type with edge reinforcing and frame elements so arranged as to eliminate openings or gaps at the corners and thereby minimize possibility of corrosion.

A further object of my invention is to so form the edge reinforcing or frame elements, at their ends, that they provide integral caps or closures for the ends of the adjacent corrugations.

Other objects of the invention will more clearly appear from the description and claims hereinafter following, considered in connection with the drawings.

In the drawings forming a part of this specification, Figure 1 is a side elevational view of a double car door arrangement showing my improvements incorporated therein. Figure 2 is a horizontal sectional view upon an enlarged scale, corresponding to the line 2-2 of Figure 1, parts being broken away in order to better accommodate the figure on the sheet. Figure 3 is a vertical sectional view corresponding to the line 3-3 of Figure 2. Figure 4 is an elevational view of the blank used in forming the reinforcing edge members of the door. Figure 5 is a perspective view of one of said reinforcing members in its completed form. In Figures 3, 4 and 5, parts are broken away in order to accommodate the views on the sheet. Figure 6 is a

top plan view of the member shown in Figure 4. Figure 7 is a horizontal sectional view of the member shown in Figure 4, corresponding to the line 7-7 thereof. And Figure 8 is a detail vertical sectional view through one of the horizontal edges of the door.

In said drawings, 10-10 denote the usual sheathing of the side wall of a car, the same having a door opening 11 formed therein, which is defined by vertical posts 12-12 with which are associated wood fillers 13-13. The posts 12, as shown, are in the form of Z-bars, the webs of which extend perpendicularly to the wall of the car. In the double door arrangement shown, the main door is indicated generally by the reference character A and the auxiliary door by the reference character B, both of said doors being of the bottom hung type, supported by roller brackets 14-14, which are indicated conventionally. Any suitable operator may be used for forcing the doors to finally closed position and to initiate the opening movement, one such form of device being indicated conventionally at 15.

Each of the doors A and B is generally of the same construction except for variations occurring at the forward or meeting edges of the doors, as hereinafter pointed out. Each door has the main body portion thereof comprised preferably of three sheet metal panels 16, 17 and 18, riveted or otherwise united along their horizontal overlapped edges, all of said panels being provided with integral, outwardly disposed horizontal reinforcing corrugations 19-19.

Along each vertical edge, the sheet metal of the door is formed with what may be termed a partial corrugation, the same being obtained by extending the sheet metal at an incline outwardly and toward the corresponding edge of the door, as indicated at 20, the sheet metal then terminating in a flat marginal section 21 which is offset outwardly from the main plane of the door and parallel thereto. As will be clear from an inspection of Figure 1, all of the horizontal corrugations 19 merge at their ends with the said partial vertical edge corrugations just described, to thereby obtain a very rigid

integral construction consistent with the gauge of metal used. As apparent from Figure 5, said vertical edge corrugations are terminated just short of the top and bottom edges of the door so that the ends of said corrugations are closed by the portion indicated at 22. As indicated in Figure 8, the extreme top and bottom shorter horizontal corrugations are reinforced against collapse by bridging plates 23 applied on the inner side of the door, said plates being secured along their edges by riveting or otherwise, to the main sheet metal at opposite sides of the mouth of the corresponding horizontal 15 corrugation.

To rigidify the vertical edges of the door and to minimize any possibility of twisting about vertical axes, I employ edge reinforcing members designated generally by the 20 reference characters C, D, E and F, those referenced C and D being on the auxiliary door and those referenced E and F being on the main door. The two members C and F are of like construction and those referenced 25 D and E are of similar construction but vary in certain details, as hereinafter described.

Referring to the reinforcing members C and F, each is of generally Z-cross section having an outer vertically extending flange 30 24 overlapped with and riveted or otherwise secured to the corresponding adjacent sheet metal flange 21; a web section 25 extending inwardly and perpendicular to the main plane of the sheet metal; and a second flange section 26 approximately in the main plane of the sheet metal and extending outwardly from the edge of the door, said flange section 26 terminating in an inturned narrower buffer or guard section 27, as best illustrated 35 in Figure 2. As shown in Figure 5, the outer flange section 24 of each member C or F is merged or united with the metal of the remaining portions by inclined end cap sections or walls 28-28 near the upper and 40 lower ends of the member. These end or cap sections 28 in turn merge with small end portions 29-29, the latter being outwardly offset from the plane of the other flange section 26, as indicated at 30, a distance corresponding 45 to the thickness of the sheet metal of the main door portion. As clear from Figures 3 and 5, the end cap sections 28 of the reinforcing members C and F overlap the corresponding end sections 22 of the partial corrugations 50 so that, when the reinforcing members are applied, the ends of the edge corrugations of the door are completely covered or closed thereby preventing rain or other foreign matter 55 from entering into the corrugations, as will be apparent.

Associated with each of the reinforcing members C and F are vertically extending bridging plates 31, each of which is riveted or otherwise secured to the main sheet metal 60 portion of the door inwardly of the corruga-

tion and to the corresponding outwardly extended flange section 26 of the reinforcing member C or F. In this manner, the complete corrugation formed by the sheet metal of the main door portion and the reinforcing member is strengthened against collapse and the reinforcing member prevented against turning or twisting about a vertical axis. 70

Associated with each rear edge of the main and auxiliary doors is a weather seal arrangement. Each said arrangement comprises a sealing strip 32 secured to the door and a cooperating sealing strip 33 secured to the corresponding door post 12. The sealing strip 32 has a flat flange section 34 lying 75 against the inner face of the bridging strip 31 and secured to the door by the same rivets which secure the strip 31. The outermost edge of the flange section 34 preferably abuts the abutment or guard section 21 of the reinforcing member C or F so that when a blow or pressure is applied to the guard section, the securing rivets will be placed under double shear to thereby minimize tendency of the rivets to tear out and preventing distortion 80 of the sealing strip 32. The latter also has an inwardly and forwardly inclined sealing flange proper 35 adapted to cooperate with a reverted flange 36 carried by the sealing strip 33. 85

The reinforcing member E at the forward edge of the main door A is similar to the reinforcing member F and is applied in the same manner and associated with a similar bridging strip 31, the only difference being that, at its extreme forward edge the member F is formed with an outwardly extended sealing section 37 instead of an inwardly extending section 27. 95

The reinforcing member D at the front edge of the auxiliary door B is similar to the member C except that, at the front edge of the flange section 126 the member D is extended perpendicularly outward, as indicated at 38, and thence forwardly and outwardly, as indicated at 39, to provide a weather sealing and guiding construction cooperable with the sealing section 39 of the member E. In this connection, it will be observed that the free edge of the guiding and sealing flange 39 is closely adjacent the web section 25 of the member E so that there is only slight possibility of rain, snow or the like being driven into the pocket formed on the inner side of the flange 39. 100 When the car is in motion toward the right, as viewed in Figure 2, the member E acts as a deflector which practically eliminates any possibility of foreign matter being driven into the joint, as will be apparent. When the car is traveling in the opposite direction, that is, to the left as viewed in Figure 2, the outwardly sloping flange 39 will deflect most of the rain or other foreign matter and sufficiently to practically prevent any rain or other foreign matter passing through the 115 120 125 130

joint where the two sections 37 and 38 meet.

In the construction at the forward edge of the auxiliary door B, the usual bridging strip 31 is omitted in view of the arrangement 5 for the nailing strip. A nailing strip support 40 is provided, of special formation, the same having a web 41 arranged perpendicular to the plane of the door and extending inwardly therefrom, an outer flange 42 arranged parallel to the plane of the door and extending away from the door, the outermost portion of the flange 42 being deflected inwardly as indicated at 42 so as to provide a camming or wedge face for the forward 10 edge of the main door when the latter is moved to closed position. Said support 40 is united to the door B by a series of rivets 43 extended through the flange 42 and flange section 126 of the member D and, in addition, 15 is united to the main portion of the door B by diagonally disposed plate 44, the inner and outer edges 45 and 46 of which are riveted or otherwise secured to the web 41 of the support and the main sheet metal portion of 20 the door, respectively.

A wood nailing strip 47 is secured to the support 40 by any suitable means. Preferably the lintel and threshold of the car will be provided with suitable stops to be engaged 25 by the post construction when the auxiliary door is in its closed position, one such bracket being indicated conventionally at 48 and having a lug or stop 49 against which the post 47 is adapted to abut. The auxiliary door may 30 be locked in its closed position by any suitable means such as a vertically slideable bolt indicated at 50 and which is carried by a bracket attached to the support 40, it being understood that the end of the bolt 50 enters 35 a corresponding opening in the threshold or lintel bracket 48, as the case may be.

In actual practice, the edge reinforcing members C, D, E and F will be of considerably heavier gauge than that of the sheet 40 metal forming the main portion of the door, in order to provide the necessary strength. With the construction so far described, it will be apparent that a very rigid edge construction is formed, with a minimum number of 45 parts, the use of interior braces for the edge corrugations being entirely eliminated and the weather sealing or buffing sections being formed integral with the reinforcing members. At the same time, the vertical edge 50 corrugations are entirely closed in to avoid entrance of rain or the like, which would otherwise tend to produce corrosion.

In manufacturing the reinforcing edge members, a very simple and inexpensive 55 method may be employed, as follows, reference being had particularly to Figures 4, 6 and 7. An elongated rectangular plate of the proper gauge and dimensions is first obtained. This plate is then flanged along its 60 side edges, as indicated at 51—51 and pressed

with a longitudinally extending centrally disposed corrugation 52 to the opposite side of the plane of the plate. Said corrugation 52 will be of generally rectangular cross section, as shown in Figure 7, and will terminate 70 a short distance from the end edges of the plate, thereby leaving integral end walls or cap sections 53—53, the slope of which will correspond to the slope of the end sections 22 of the partial corrugations of the main sheet 75 metal body portions of the door. Beyond the ends of the corrugation 52, the plate will be slightly outwardly offset as indicated at 54 in Figure 6, the offset corresponding to the thickness of the metal used in the sheet metal 80 body portion of the door. With the plate thus formed, the same is slit or parted lengthwise and centrally thereof so as to thereby simultaneously produce two like or complementary reinforcing members. In Figures 4, 85 6 and 7, I have illustrated the method of manufacture of the two reinforcing members C and F. As will be understood, the same method will be employed in manufacturing the reinforcing members D and E, the only 90 difference being in the flanging to provide the weather sealing sections 37 and 38, as will be obvious. In this manner, the reinforcing members may be manufactured in pairs simultaneously, by very simple flanging and 95 pressing operations, thus reducing the cost of manufacture to a minimum.

Although I have herein shown and described what I now consider the preferred manner of carrying out the invention, the 100 same is merely illustrative and I contemplate all changes and modifications that come within the scope of the claims appended hereto.

I claim:

1. In door construction, the combination 105 with a sheet metal body portion laterally offset along one edge to provide a partial corrugation terminating in a flange parallel to the main plane, the ends of said partial corrugation terminating within the area of the 110 body portion; and means for reinforcing said edge including a bar of angular cross section extending lengthwise of said edge and provided adjacent its ends with cap sections 115 adapted to overlap the ends of said partial corrugation.

2. In door construction, the combination 120 with a main sheet metal body portion having an offset along one edge thereof and of lesser length than said edge, said offset extending lengthwise of said edge and having integral sections at the ends thereof merging with the main portion of the sheet metal; and a reinforcing bar extending along 125 said edge and secured to said offset portion, said bar being formed at its ends with cap sections overlapping said end portions of said offset.

3. In door construction, the combination 130 with a main sheet metal body portion having

- an offset along one edge thereof and of lesser length than said edge, said offset extending lengthwise of said edge and having integral sections at the ends thereof merging with the main portion of the sheet metal; a reinforcing bar extending along said edge and secured to said offset portion, said bar being formed at its ends with cap sections overlapping said end portions of said offset; and a sheet metal strip extending lengthwise of said edge and secured along its edges to the main sheet metal body portion and to said bar.
4. In car door construction, an auxiliary door for a double door arrangement, said auxiliary door comprising: A sheet metal body portion having partial corrugations along each vertical edge, each said partial corrugation including an outwardly inclined section and a marginal section parallel to the main plane of the sheet metal body portion; a reinforcing bar along the rear edge and secured to the corresponding partial corrugation; a reinforcing bar secured along the forward edge of said door, said bar having an outer flange section overlapping and secured to said marginal section of the corresponding partial corrugation, an inwardly extending web section, and a forwardly extending flange section; a nailing strip support of angular cross section having one flange thereof secured to said forwardly extending flange section; and bracing means extending between and secured to another section of said support and the main body portion of the sheet metal, respectively, each of said reinforcing bars having integral cap portions at its ends overlying and closing the ends of the corresponding partial corrugations.
5. In car door construction, a main door of a two-door type closure, said main door comprising a main body section of sheet metal having partial corrugations formed therein along each vertical edge; a reinforcing bar extending along and secured to the rear edge of said door, said bar having a flange section overlapping and secured to the corresponding edge portion of the partial corrugation and an integral inwardly extended buffer flange; a reinforcing bar secured to the forward edge of said door and having a flange section overlying and secured to the corresponding adjacent edge portion of the partial corrugation, a web section extending perpendicularly inwardly therefrom, a flange section extending from the web section and parallel to the main plane of the door, and an outturned weather sealing section at the forward edge of said last named flange section; bridging strips along each vertical edge, each secured respectively to the main sheet metal body portion inwardly of the corresponding partial corrugation and to the reinforcing bar at the opposite side of the partial corrugation.

6. In car door construction, an auxiliary door for a double door arrangement, said auxiliary door comprising: A sheet metal body portion having partial corrugations along each vertical edge and terminating short of the top and bottom edges of the door; a reinforcing bar along the rear edge and secured to the corresponding partial corrugation; a reinforcing bar secured along the forward edge of said door, said bar having an outer flange section overlapping and secured to the corresponding adjacent portion of the partial corrugation, an inwardly extending flange section, and a forwardly extending flange section; a nailing strip support of angular cross section having one flange thereof secured to said forwardly extending flange section; and bracing means extending between and secured to another section of said support and the main body portion of the sheet metal, respectively, each of said reinforcing bars having integral cap portions at its ends overlying and closing the ends of the corresponding partial corrugations.

7. In car door construction, a main door of a two-door type closure, said main door comprising a main body section of sheet metal having partial corrugations formed therein along each vertical edge and terminating short of the top and bottom edges of the door; a reinforcing bar extending along and secured to the rear edge of said door, said bar having a flange section overlapping and secured to the corresponding edge portion of the partial corrugation and an integral inwardly extended buffer flange; a reinforcing bar secured to the forward edge of said door and having a flange section overlying and secured to the corresponding adjacent edge portion of the partial corrugation, a web section extending inwardly therefrom, a flange section extending from the web section and parallel to the main plane of the door, and an outturned weather sealing section at the forward edge of said last named flange section; bridging strips along each vertical edge, each secured respectively to the main sheet metal body portion inwardly of the corresponding partial corrugation and to the reinforcing bar at the opposite side of the partial corrugation, each of said reinforcing bars having integral cap portions at its ends overlying and closing the ends of the corresponding partial corrugations.

8. As an article of manufacture, a reinforcing edge bar for doors, said bar having a flange extending the full length thereof, a web at an angle to said flange terminating a short distance inwardly of each end of said flange; a second flange substantially at right angles to said web and of approximately the same length as the web; and end sections in line with said last named flange extending from said flange to approximately

the plane of the first named flange, said sections being adapted to function as caps.

9. In door construction, the combination with a main door portion comprised of sheet metal, the sheet metal of said main door portion along one edge thereof being extended first outwardly from the original plane of the sheet metal and thence parallel to but offset from said original plane and thereby forming a partial corrugation along said edge of the door, the said partial corrugation terminating, at its ends, a short distance from each of the corresponding adjacent edges of the door and the ends of said partial corrugation being formed by portions of the sheet metal; of a reinforcing bar for said edge of the door, said bar having an outer flange lapped and secured to said offset portion of the partial corrugation, a web section extending inwardly to substantially the original plane of the main sheet metal portion and a flange extended outwardly from said web section, said bar having also portions at the ends of the first named flange thereof lapping with said end portions of the partial corrugation of the main door portion, whereby a complete corrugation with closed ends is formed along said edge of the door.
- 30 10. A door comprising a sheet metal main portion formed with a partial corrugation along one edge with integral end formations at the end of said partial corrugation, and a reinforcing member formed with complementary partial corrugation and end formations, the complementary portions of said member and sheet metal main portion being overlapped and secured to thereby provide a complete corrugation with closed ends.
- 40 In witness that I claim the foregoing I have hereunto subscribed my name this 29th day of March, 1929.

FRANK DITCHFIELD.
